UNITED STATES PATENT OFFICE.

WALTER N. BURNHAM, OF BALLSTON SPA, NEW YORK, ASSIGNOR TO THE BEAVER COMPANY, OF BEAVER ROAD, BUFFALO, NEW YORK, A CORPORATION OF OHIO.

SUCTION CYLINDER.

Application filed November 9, 1920. Serial No. 422,773.

To all whom it may concern:

Be it known that I, WALTER N. BURNHAM, a citizen of the United States, residing at Ballston Spa, in the county of Saratoga and State of New York, have invented certain new and useful Improvements in Suction Cylinders; and I do hereby declare the following to be a full, clear, and exact description of the invention, such as will enable others skilled in the art to which it appertains to make and use the same.

My invention is an improvement in paper making machines and the object of the invention is to provide in a machine of the character specified, a new and improved construction of laying wheel or cylinder wherein felts and Fourdrinier wires are dispensed with.

Another object is to provide mechanism in connection with the wheel for permitting a maximum amount of moisture to be removed from the sheet while on the cylinder.

Another object is to provide means in connection with the moisture removing mechanism for permitting the force of the suction exerted in removing the moisture to be varied at will.

Another object is to provide mechanism in connection with the cylinder for facilitating the removal of the sheet and for cleaning the wheel.

In the drawings:

Fig. 1 is a top plan view of the improved machine.

Fig. 2 is a section on the line 2—2 of Fig. 3.

Figs. 3 and 4 are sections on the lines 3—3 and 4—4 respectively of Fig. 2.

Fig. 5 is an end view.

In the present embodiment of the invention there is provided a suitable tank 1 for the pulp solution and within this tank is mounted the laying cylinder to be presently described in detail. This cylinder rotates upon a hollow fixed shaft 2 which is mounted in the ends of the tank, and upon the shaft a sleeve or valve 3 is arranged; the sleeve or valve fitting the shaft perfectly but being movable angularly with respect thereto.

The ends of the sleeve and shaft are closed by heads 4 and 5, the head 5 having near its top an outlet 6 for connection with a vacuum pump and having near its bottom an outlet 7 for connection with a water pump. This outlet 7 has interposed between

the same and the shaft a trap indicated at 8, to retain a predetermined amount of liquid in the shaft.

Upon the sleeve there is mounted the cylinder, indicated generally at 9, constructed in a manner to be presently described. The lower half of this cylinder dips within the solution in the tank, as indicated in Fig. 3 and the peripheral surface of the cylinder is formed of wire, the wire being preferably in the form of a backing wire of close mesh and a face wire of finer mesh arranged over the backing wire.

Referring to Fig. 2 it will be seen that the cylinder is of less length than the shaft and the sleeve valve, both shaft and valve extending beyond the cylinder at each end, and the interior of the cylinder between the valve and the periphery thereof is divided into compartments by partitions 9' which are inclined in the same direction as will be evident from Fig. 3.

It will be noticed referring to Fig. 2 that the cylinder is composed of a hub portion which fits upon the sleeve and is rotatable thereon, a rim portion and arms connecting the hub portion with the rim portion. These arms are inclined and the partitions are supported by the arms. The arrangement is such that when the cylinder rotates in the pulp solution, referring to Fig. 3, the partitions as they rise from the solution will incline downwardly and inwardly to provide for free drainage.

The shaft 2 is provided with a series of 90 slots or ports 10, covering about one-fourth of the area of that portion of the periphery which is within the cylinder and these slots are inclined at an angle, slightly less than that of the partitions 9'. The sleeve 3 is also provided with ports or openings 11 which are adapted to register with those of the shaft under certain conditions, and the hub portion of the cylinder has ports or passages 12 throughout its extent which are also adapted to come into register with the ports 10 and 11 under conditions to be presently described.

Referring to Fig. 1 it will be noted that the vat consists of a central compartment 105 in which the cylinder rotates and end compartments divided from the central compartment by partitions 57, and as shown in Fig. 2 these partitions are shaped at their upper ends to fit against the ends of the 110

cylinder, the rim portions of the end sections of the cylinder moving in close contact with the said partitions 37.

The central compartment has an overflow 41, and this overflow is controlled by a gate 42 which is mounted to move in guides 43 on the wall of a chute or extension 44. The gate may be raised and lowered by means of a rack bar 45 which is connected there-
with and which engages the teeth of a pinion 46 on a shaft journalled in the super-structure, and having a hand wheel as shown for manipulating the same. The level of the liquid in the central compartment will 10 depend upon the height of the top of the gate and all excess liquid will flow over the gate into the overflow.

The level of the liquid in the lateral compartments is controlled by a gate 47, which 20 is mounted to move in guides 48 in a chute or extension 49. This chute or extension is arranged in one of the lateral compartments in the front of the vat and the gate has a rack bar 50 which meshes with the pinion 51 on a shaft 52 journalled in the super-structure and having a hand wheel for turning the same.

The shaft 52 and the shaft carrying the pinion 46 have pawl and ratchet mechanism indicated at 53 for holding them in adjusted position and it will be noticed, referring to Fig. 3, that the level of the liquid in the lateral compartments is at about the height of the dandy roll 32.

35 The ends of the compartments are open, but they are adapted to be closed at certain points in the rotation of the cylinder by means of arc-shaped beads 13. These beads as shown in Figs. 2, 4 and 5 are of a size to cover slightly more than one-fourth of the ends of the cylinder and they are so arranged that as the partitions 97 rise from the solution in the tank, the ends of the compartments will move between the beads and the heads will close the compartments. Each head has a pair of outwardly extending guide pins 14, which move in upstanding lugs 15 on an arc shaped bracket which is secured to the sleeve 3, and a coil spring 50 16 is arranged between the lugs and the heads acting normally to press the heads toward the cylinder ends. Each of the heads has an air pipe 17 extending therefrom which may be connected with suitable compressing mechanism.

The cylinder is rotated in the solution by means of a shaft 18 which is journalled in a super-structure 19 extending upwardly from the tank and the shaft is connected to a source of power by means of a pulley 20. The shaft carries pinions 21 which mesh with gear teeth 22 on the ends of the cylinder, each end of the cylinder having an annular series of teeth.

45 The valve or sleeve 3 is shifted angularly

by means of shafts 23. These shafts carry worms 24 which mesh with arc-shaped rack bars 25 on the sleeve. The shafts 23 are connected to a shaft 26 extending longitudinally of the super-structure 19 before mentioned by means of bevel gearing 27 and each has a hand wheel 28. By means of the hand wheel 28 the position of the sleeve valve with respect to the central shaft may be varied to bring the ports 11 thereof more or less into register with the ports 10 of the shaft, and it will be noticed referring to Fig. 3 that the sleeve valve has the same number of ports as the shaft. The pulp is fed to the tank beneath a false bottom 29.

50 Referring to Fig. 3 it will be seen that the connection 30 with the source of supply opens at the front of the tank beneath the false bottom and that there is a space at the rear of the tank between the false bottom and the rear wall through which the pulp feeds to the cylinder.

The operation of the machine is as follows—

With a supply of stock in the tank or vat 90 and with the cylinder rotating, the stock flows beneath the false bottom coming up on the rear side and coming in contact with the cylinder at the point where the cylinder enters the pulp stock. The water on the inside of the cylinder, that is, the water in the central compartment is kept at as low a level as possible by means of a pump connected with the overflow pipe 41. This causes the pulp stock, during the submersion of the cylinder in the stock, to adhere to the peripheral surface of the cylinder. As the cylinder leaves the stock level, the openings of the cylinder will come into register with the openings of the valve and shaft and the partial vacuum in the shaft will act upon the formed sheet on the wire, extracting the water and moisture. Soon afterwards the ends of the compartments move between the beads 13 thus sealing the said ends and sealing the compartments except at the periphery of the cylinder.

100 The vacuum in the shaft acts thus upon the formed sheet on the wire thoroughly extracting the water and moisture. This exhausting continues until the compartments are near the ends of the beads 13. As they approach the rear ends of the beads, and just before they pass out of contact with the beads, air under pressure is forced into the compartments, and this air assists the stripper 33 in removing the sheet 31 from the wire. Air under pressure is introduced into the last two compartments which are in contact with the beads.

110 The cylinder is built up from a series of intermediate sections, which are similar, and two end sections. Each of the sections consists of a hub portion, a rim portion and 115 a rim connecting the hub and the rim nor-

120 125 130

tion. Rods indicated at 54 are arranged between the end sections, the ends of the rods engaging openings indicated at 55 in the rim portions of the end sections, and these rods engage notches 56 in the rim portions of the central sections. Thus a cylinder of any desired length may be built up. The partitions 9' are preferably of heavy sheet brass.

When air under pressure is admitted to 10 the two compartments adjacent to the ends of the heads 13, the pressure not only loosens the sheet, but also cleans the wire.

I claim:

1. In a paper making machine, a hollow shaft adapted for connection with exhausting mechanism, a laying cylinder having a hub mounted on the shaft and having radially extending compartments opening through the hub, the shaft having ports with which 20 the compartments register as they leave the stock and means for varying the area of the ports of the pipe at will.

2. In a paper making machine, a hollow shaft adapted for connection with exhausting mechanism, a laying cylinder having a hub mounted on the shaft and having radially extending compartments opening through the hub, the shaft having ports with which the compartments register as they leave the 30 stock and means for varying the area of the ports of the pipe at will, said means comprising a sleeve valve mounted to rotate on the shaft between the hub and the shaft and having ports adapted to register with those of the shaft.

3. In a paper making machine, a hollow shaft adapted for connection with exhausting mechanism, a laying cylinder having a hub mounted on the shaft and having radially 40 extending compartments opening through the hub, the shaft having ports with which the compartments register as they leave the stock, and means for varying the area of the ports of the pipe at will, and means for closing the ends of the compartments as they come into register with the ports of the shaft and for holding them closed until they pass out of register with said ports.

4. In a paper making machine, a hollow shaft adapted for connection with exhausting mechanism, a laying cylinder having a hub mounted on the shaft and having radially extending compartments opening through the hub, said compartments being normally 55 open at the end, the shaft having ports with which the compartments register as they leave the stock and normally stationary heads for closing the ends of the compartments as they come into register with the ports of the shaft and for holding them closed until they pass out of register with said ports.

5. In a paper making machine, a hollow shaft adapted for connection with exhausting mechanism, a laying cylinder having a

hub mounted on the shaft and having radially extending compartments opening through the hub, said compartments being normally open at the end, the shaft having ports with which the compartments register as they leave the stock, and means for closing the ends of the compartments as they come into register with the ports of the shaft, and means for introducing air under pressure in 70 said compartments as they move out of register with said ports. 76

6. In a paper making machine, a hollow shaft adapted for connection with exhausting mechanism, a laying cylinder having a hub mounted on the shaft and having radially extending compartments opening through the hub, the shaft having ports with which the compartments register as they leave the stock, and means for introducing air under 80 pressure into the ends of said compartments as they move out of register with the ports of the shaft. 85

7. In a paper making machine, a hollow shaft adapted for connection with exhausting mechanism, a laying cylinder having a hub mounted on the shaft and having radially extending compartments opening through the hub, the shaft having ports with which the compartments register as they leave the stock, means for withdrawing water from the cylinder above a predetermined level, and means outside of said shaft for introducing air under pressure into 90 said compartments. 95

8. A paper making machine comprising a vat for the pulp stock, a hollow shaft supported within the vat and adapted for connection with exhausting mechanism, a sleeve valve mounted to move angularly of the shaft, a laying cylinder mounted to rotate on the valve, said cylinder being divided into a series of radially extending compartments by imperforate compartments extending longitudinally thereof, the compartments opening at the periphery of the 100 shaft, the shaft and the sleeve having registering ports at the point where the compartments emerge from the stock and the compartments having openings for registering with said ports, means at each end of 105 the cylinder for closing the ends of the compartments while the ports thereof are in register with the ports of the valve. 110

9. A paper making machine comprising a vat for the pulp stock, a hollow shaft supported within the vat and adapted for connection with exhausting mechanism, a sleeve valve mounted to move angularly of the shaft, a laying cylinder mounted to rotate on the valve, said cylinder being divided into a series of radially extending compartments by imperforate partitions extending longitudinally thereof, the compartments opening at the periphery of the shaft, the shaft and the sleeve having registering 120 125 130

- ports at the point where the compartments emerge from the stock and the compartments having openings for registering with said ports, means at each end of the cylinder for closing the ends of the compartments while the ports thereof are in register with the ports of the valve, and means for introducing air under pressure to the compartments as they move out of register with the ports of the valve to assist in stripping the sheet from the cylinder.
10. A paper making machine comprising a vat for the pulp stock, a hollow shaft supported within the vat and adapted for connection with exhausting mechanism, a sleeve valve mounted to move angularly of the shaft, a laying cylinder mounted to rotate on the valve, said cylinder being divided into a series of radially extending compartments by imperforate partitions extending longitudinally thereof, the compartments opening at the periphery of the shaft, the shaft and the sleeve having registering ports at the point where the compartments emerge from the stock and the compartments having openings for registering with said ports, and means for withdrawing the water from the shaft above a predetermined level.
15. 11. A paper making machine comprising a vat for the pulp stock, a hollow shaft supported within the vat and adapted for connection with exhausting mechanism, a sleeve valve mounted to move angularly of the shaft, a laying cylinder mounted to rotate on the valve, said cylinder being divided into a series of radially extending compartments by imperforate partitions extending longitudinally thereof, the compartments opening at the periphery of the shaft, the shaft and the sleeve having registering ports at the point where the compartments emerge from the stock and the compartments having openings for registering with said ports, means at each end of the cylinder for closing the ends of the compartments while the ports thereof are in register with the ports of the valve, and means for introducing air under pressure to the compartments as they move out of register with the ports of the valve to assist in stripping the sheet from the cylinder.
20. 12. In a paper making machine, a hollow shaft, and a laying cylinder mounted to rotate on the shaft and having independent longitudinally extending compartments extending from the hub to the periphery, a vat for containing stock in which the cylinder is mounted to rotate, means for maintaining the water within the cylinder at a lower level than the stock within the vat to cause the pulp to adhere to the cylinder, a variable communication between the shaft and the cylinder compartments established as the said compartments leave the stock, means for closing the ends of the compartments when said connection is established, and means in connection with said closing means for introducing air under pressure into the compartments as they leave the closing means.
25. 13. In a paper making machine, a hollow shaft, and a laying cylinder, mounted to rotate on the shaft and having independent longitudinally extending compartments extending from the hub to the periphery, a vat for containing stock in which the cylinder is mounted to rotate, means for maintaining the water within the cylinder at a lower level than the stock within the vat to cause the pulp to adhere to the cylinder, a variable communication between the shaft and the cylinder compartments established as the said compartments leave the stock, means for closing the ends of the compartments when said connection is established.

In testimony whereof I affix my signature.

WALTER N. BURNHAM.
